UNITED STATES PATENT OFFICE

2,438,419

INSULATOR

Paul A. Schmidt, near Earlville, Ill.

Application October 22, 1945, Serial No. 623,678

6 Claims. (Cl. 174—163)

1

This invention relates to insulators and more particularly to insulators for use with electric fences.

In the use of electric fences on farms, it is frequently desirable to move either the entire fence or to move the strands on the supports, such as fence posts, to change the elevation thereof. For a satisfactory insulator it is, therefore, necessary that the insulator can be easily and quickly attached to and detached from both the strands of wire and the post. It is one of the objects of the present invention to provide an insulator possessing these characteristics.

Another object is to provide an insulator which can be attached to and detached from both the wire and the post without the use of tools or special attaching devices.

Still another object is to provide an insulator which will support a strand of wire without requiring bending or twisting of the wire.

A further object is to provide an insulator which is extremely simple and inexpensive to manufacture.

The above and other objects and advantages of the invention will be more readily apparent from the following description when read in connection with the accompanying drawing, in which—

Figure 1 is a partial perspective view illustrating an insulator embodying the invention attached to a fence post;

Figure 2 is a side elevation of the insulator block;

Figure 3 is an elevation of the insulator block looking from the right of Figure 2;

Figure 4 is a perspective view of the mounting wire; and

Figure 5 is a central section through an insulator and a post on which it is mounted.

The insulator of the invention may be attached to any conventional support such as a standard metal fence post 10 formed of an L-section beam having a plurality of spaced slots 11 in one of its flanges. The posts may be supported in the ground in any desired manner at regularly spaced intervals to carry one or more strands of charged wire illustrated as a strand of conventional barbed wire 12.

The strand 12 is supported on the post by a block 13 of insulating material, such as porcelain, molded plastic or the like. The block is formed with a central opening 14 therethrough to receive the strand 12 and of a size substantially larger than the strand to permit easy passage of the barbs on the strand. To facilitate

2

drawing the strand through the opening, the ends of the opening are preferably flared or rounded, as indicated at 15, so that the barbs on the wire will slide freely through the opening.

5 To insert the strand of wire in the opening, a slot 16 is formed in one side of the block and preferably lies at an acute angle to the axis of the opening. With this construction, the wire can be passed through the slot into the opening 10 and the block can then be turned to bring the axis of the opening parallel to the wire so that the wire cannot jump out through the slot.

To support the block on the post, the block is formed throughout at least all of its periphery, 15 except the flat side in which the slot 16 is formed, with a groove 17. A mounting wire 18 bent into a general U-shape fits into the groove 17 and is of such a length that its ends will project beyond the flat side of the block in which the groove 20 16 is formed. The ends of the wire 18 are bent up into hooks 19 and 20 facing in the same direction. Preferably, the hook 20 extends slightly further beyond the edge of the block than the hook 19 for a purpose to appear later.

25 In mounting the block on a fence post of the type illustrated, the hook 19 is projected through one of the openings 11 and the block is then slid up so that the hook 19 will engage the inner face of the post. It will be observed that the space 30 between the end portions of the wire 18 where they project beyond the block is substantially equal to the distance between adjacent ends of a pair of openings 11 so that when the block is slid up as described, the hook 20 may extend 35 through another of the openings 11. Engagement of the wire 18 with the end of the last mentioned opening prevents the block from sliding down and maintains the hook 19 in engagement with the inner face of the post.

40 When the hook 20 is extended through the opening in the post, it projects beyond the inner face of the post a sufficient distance to receive a wire fastening. While no particular form of wire fastening is required, a convenient and inexpensive fastening which is readily available is 45 a conventional wire staple 21. Such a staple may be hooked over the hook 20 to engage the inner face of the post and to prevent the hook 20 from being withdrawn through the post.

50 With the insulator installed on the post and the staple 21 in place, as shown, it will be seen that the insulator is rigidly supported on the post and will hold a strand of wire at the desired position on the post. To move the insulator on the post, it is only necessary to remove the

staple 21 at which time the hook 20 can be slid out through its opening 11 and the insulator can be moved down to disengage the hook 19 from the post and permit its removal through its opening 11. The insulator can then again be fastened to the post at any desired different position or can be removed from the wire as required.

While one embodiment of the invention has been shown and described in detail, it is to be understood that this is illustrative only and is not intended to be taken as a definition of the scope of the invention, reference being had for this purpose to the appended claims.

What is claimed is:

1. An insulator comprising a block of insulating material having an opening therein through which a wire may pass and formed with a slot in one side communicating with the opening, and a wire extending around the block with its end projecting beyond one side of the block and terminating in hooks bent at right angles to the wire ends to lie parallel to the adjacent block surface and facing in the same direction.

2. An insulator comprising a block of insulating material having an opening therein through which a wire may pass and formed with a slot in one side lying at an angle to the axis of the opening, the block having a peripheral groove therein, and a wire lying in the groove with its ends projecting beyond one side of the block and terminating in hooks bent at right angles to the wire ends to lie parallel to the adjacent block surface and facing in the same direction.

3. An insulator comprising a block of insulating material having at least one flat side and an opening therethrough parallel to the flat side, the flat side being formed with a slot lying at an acute angle to the opening through which a wire may pass into the opening, and an elongated mounting member extending partially around the block with its ends projecting beyond the flat side and terminating in hooks facing in the same direction to mount the block with its flat side against a support.

4. An insulator comprising a block of insulating material having at least one flat side and an opening therethrough parallel to the flat side, the flat side being formed with a slot lying at an acute angle to the opening through which a wire may pass into the opening, the block having a groove in its periphery in a plane at right angles to the opening and extending at least throughout all of its periphery except the flat side, and a wire lying in the groove with its ends projecting

beyond the flat side and terminating in hooks facing in the same direction.

5. In combination with a fence post or the like having a series of spaced openings therein, an insulator comprising a block of insulating material having one side adapted to be mounted against the post and of a length substantially equal to the distance between adjacent edges of a pair of openings, the block having a hole centrally therethrough and a slot in said one side extending into the hole, and an elongated mounting member extending partially around the block with its ends projecting beyond said one side and terminating in hooks facing in the same direction, the hooks being formed to extend through the openings in the post with the hook facing outward from the block spaced from the post to receive a wire fastener.

6. In combination with a fence post or the like having a series of spaced openings therein, an insulator comprising a block of insulating material having one side adapted to be mounted against the post and of a length substantially equal to the distance between adjacent edges of a pair of openings, the block having a hole centrally therethrough and a slot in said one side extending into the hole, the block being formed with a peripheral groove in a plane at right angles to the opening and extending throughout at least all of its periphery except said one side, and a stiff mounting wire in the groove with its ends projecting beyond said one side and terminating in hooks facing in the same direction, the hooks being formed to extend through the openings in the post with the hook facing outward from the block spaced from the post to receive a wire fastener.
